UNITED STATES PATENT OFFICE

147,400

DESIGN FOR A JEWELRY FINDING OR SIMILAR ARTICLE

Michael Chernow, New York, N. Y.

Application May 24, 1946, Serial No. 130,054

Term of patent 7 years

(Cl. D45—1)

To all whom it may concern:

Be it known that I, Michael Chernow, a citizen of the United States and residing at New York, in the county of New York and State of New York, have invented a new, original, and ornamental Design for a Jewelry Finding or Similar Article, of which the following is a specification, reference being had to the accompanying drawings, forming part thereof, and in which

Fig. 1 is a top plan view of a jewelry finding, showing my new design,

Fig. 2 is a side elevational view thereof, and

Fig. 3 is an end elevational view thereof.

The jewelry finding may be embodied in such articles as bracelets, necklaces, earrings, brooches, clips or similar articles.

I claim:

The ornamental design for a jewelry finding or similar article, substantially as shown and described.

MICHAEL CHERNOW.
